TAPE COIL WINDER

Edward S. Larson and Harold A. Wahlstrand,
Chicago, Ill., assignors to Teletype Corporation,
Chicago, Ill., a corporation of Delaware

Application January 12, 1935, Serial No. 1,456

12 Claims. (Cl. 242—55)

The present invention relates to tape winding apparatus and is particularly concerned with take-up apparatus for coiling tape ejected from telegraph apparatus under variable conditions 5 and speeds of operation.

An object of the present invention is the provision of a power-operated device which is simple, durable, and capable of winding ejected tape with sufficient rapidity to accompany telegraph apparatus capable of constant or variable 10 speeds of operation.

The present invention features a frictionally driven tape winder having a tape slack sensing means that is governed by the quantity of ejected 15 tape in permitting or suspending the application of power to a winding reel. In addition, the present invention also embodies means for indicating by actuation of a sensory alarm apparatus when a coil of tape has been wound to pre- 20 determined proportions.

In carrying out the foregoing objects and features of the invention, a preferred embodiment comprises a unitary structure secured to a base casting and including a horizontally mounted 25 reel frictionally driven by worm and gear connection from an electric motor. A winding guide arm pivotally presented with respect to said reel is capable of being rocked out of operative guiding position, during which movement it opens 30 a tape stop switch. The latter functions to open a circuit for energizing the operating motor of the unit.

The unit also includes a buzzer that is electrically arranged in series with the motor but 35 which is ordinarily shunted by a switch that is mechanically actuated when the accumulation of tape in a coil becomes great enough so that the coil acquires a predetermined diameter. When this occurs, the periphery of the coil coming 40 into engagement with the last mentioned switch opens the shunt, cutting the buzzer in series with the motor and resulting in an audible signal while also concurrently arresting the motor by reason of the high resistance of the 45 buzzer operating element which is located in the motor circuit.

For a more comprehensive understanding of the present invention, reference should be had to the accompanying drawing and to the following specification in which like designating characters indicate similar parts throughout, and in which,

Fig. 1 is a side elevation of a tape coil winder embodying certain features of the present invention;

Fig. 2 is a plan view of the apparatus indicated in Fig. 1;

Fig. 3 is a detailed sectional view taken approximately on line 3—3 of Fig. 2, and

Fig. 4 is a wiring diagram featuring the electrical hookup of the apparatus indicated in the aforesaid figures.

The reference character 11 indicates generally a base casting upon which the essential operating elements are mounted. An enveloping housing, not shown, may be employed if desired, which may enclose a portion of the mechanism excepting the reel and the tape stop arm about to be described. A small electric motor is indicated at 12 and is provided with a worm gear 13 with which 15 it drives worm wheel 14. The latter is carried upon a horizontal shaft 15 and is frictionally held by a packing assembly 16 and spring spreader 17.

The shaft 15 is journaled at 18 and 19 in a pair of standards 21 and 22 that are suitably 20 mounted in an upright position upon the base casting 11. On its opposite end, shaft 15 carries secured to it a spool 23 tapered slightly as best seen in Fig. 2. The spool has associatively secured to it a flange disc 24 and, to permit the 25 starting end of a tape to be quickly and readily secured, the spool or arbor 23 has formed with it a series of inwardly extending notches 25, affording acute angular relation with a tangent coincident with the incoming tape. To diminish 30 the mass of the reel or arbor 23, its internal portion is hollowed away as best indicated at 26, Figs. 1 and 2. Peripheral sections of the reel are also cut away as indicated at 27, and in the flange 24, elongated holes 28 are provided in registration 35 with the cut away sections 27 so as to permit an operator to insert his index finger and thumb for removing the tape coils after they have been completed. The taper of the spool as afore- 40 described also assists toward this end.

Ordinarily the frictional engagement between the driven wheel 14 and the shaft 15 might be expected to operate so as to afford a slip when the tape 29 becomes taut. This has not been found expedient, however, because of the necessary frictional resistance in the elements 16 as compared with the susceptibility to rupture and disfiguration on the part of the perforated tape 29. Accordingly, means are provided whereby even slight resistances to the movement of the tape 50 29, causing the latter to become taut, immediately suspends the driving connection between the motor 12 and the reel 23, preventing any damage to the tape 29 which might otherwise ensue.

This is obtained by the provision of a gear 31 loosely carried by shaft 15 that is adapted to drive a pinion 32 formed with the stud shaft 33 pivotally carried by trunnions 34 formed in the standards 21 and 22. The gear 31 is loosely carried upon shaft 15 and is driven thereby through the instrumentality of a ratchet wheel 35 and pawl 36 that is pivotally secured on one side of the gear wheel 31 and is spring urged into engagement with the ratchet 35.

The aforescribed pawl and ratchet structure permits the free movement of the reel 23 and shaft 15 in a clockwise direction, as viewed in Fig. 1, when the gear wheel 31 becomes immovable by reason of the locking apparatus about to be described. In this way the tape 29 may be unwound from the reel 23 as for purposes of inspection, following which the driving motion of reel 23, in a counterclockwise direction, may quickly rewind the withdrawn section of the tape and reinstate normal winding operation.

The shaft 33 carries a pair of vanes 37 which are rotated in a clockwise direction, as viewed in Figs. 1 and 3, as the reel 23 is moved in a counterclockwise direction.

A so-called tape stop arm 38 is pivotally carried upon a shaft 39 and comprises a bail section 41 having a pair of ears 42 to one of which there is secured an elongated section of rod which properly forms part of the arm 38 and which terminates with a perpendicular section 43 turned downwardly as at 44 to confine and align the incoming tape 29.

The shaft 39 is secured to the standards 21 and 22 by set screws 45 and serves to also support a larger bail 46 which surrounds the aforescribed bail 41 and has at one of its ears 47 a switch actuating projection 48, see Figs. 2 and 3. A toggle spring 49 secured at one end to the base casting 11 and at its other end to the binding post 51 tends to maintain the bail 46 in either of its extreme positions. The other ear of bail 46 is elongated and forms a guide 52 for assisting in confining the tape 29 as it is rolled into coils.

At its opposite end, guide 52 is cut away as at 53 to afford a finger piece whereby the guide may be manually rotated in opposition to spring 49 from the position indicated in solid lines in Fig. 1 to that indicated in broken lines, permitting the tape coil to be removed or a new coil to be started.

As the bail 46 is rocked about shaft 39, it engages a screw head 54 of a screw carried by the internal bail 41, causing the latter to be simultaneously rotated about shaft 39 and to assume a position approximately as that indicated in broken lines in Fig. 1, or until a suitable stop element is encountered. As the internal bail 41 is rocked counterclockwise, a lip 56 integrally formed with it moves from a position such as that indicated in full lines in Fig. 3 to that indicated in broken lines, coming into the path of one or the other of the revolving vanes 37 and arresting the movement of shaft 33 thereby. The resistance to motion on the part of shaft 33 acting through pinion 32 arrests gear 31, which through pawl 36 and ratchet wheel 35 arrests shaft 15. Thereafter the motor 12, continuing to drive gear 14, causes the latter to slip between its friction discs 16.

The raising of tape stop arm 38 either by manual actuation of guide 52 or by the taut condition of the tape 29 causes the projection 56 to rise sufficiently so that it is presented into the path of the revolving vanes 37, blocking the next one of these elements which it encounters. If the

arm 52 is rotated into its broken line position, its extension 48 recedes from contact button 57, as will be noted from Fig. 4, breaking the circuit originating at battery or current source 59 and continuing over line 61 through the contact 58, line 62, to the motor 12, thence out over lines 63 and 64, contact pair 65, lines 66 and 67 to the opposite source of the current potential 59.

When a coil becomes large enough in diameter so that its periphery contacts the insulated roller 10 68, a slightly further enlargement thereof depresses the contactor 69 of contact pair 65, withdrawing it from engagement with its contact point and breaking the circuit as noted in Fig. 4. In this case, however, the circuit is diverted at 15 point 71 of line 63, continuing thereafter over line 72 through the high resistance winding of buzzer 73, thence out over lines 74 and 67. The resistance of motor 12 is insufficient to impair the operation of buzzer 73, therefore the latter, 20 under the aforescribed circumstances, renders an audible signal, indicating that a full roll of tape has been wound. The resistance of buzzer 73, however, in series with the operating circuit of motor 12, suffices to impair the operation of 25 the latter, causing the motor to be arrested simultaneously as the audible signal is sounded.

While the present invention has been explained and described with reference to a particular mechanism and embodiment, it will be understood that numerous modifications and variations may be instituted without departing from the spirit or scope thereof. Accordingly, it is not intended to be limited in the concept of this invention to any of the details illustrated in the accompanying drawing nor to the specific language of the foregoing specification except as indicated by the hereinafter appended claims.

What is claimed is:

1. In an apparatus, an electric motor, an electric alarm device, and a circuit connecting said motor and said device with a source of current potential, including a circuit breaker arranged in parallel with said alarm device and adapted when opened to introduce said device in series with 45 said motor.

2. A tape winder including an electric motive power supply source, an electric alarm device, a circuit connecting said power source and said alarm device with an operating potential, and a switch controlled by said tape winder for shunting 50 said alarm device.

3. A tape winder including a reel, a motor, frictional driving connection between said motor and said reel, a circuit between said motor and a source of current supply, and a resistance element in series with said motor under the control 55 of tape wound on said reel to arrest the operation of said motor.

4. In a tape winding mechanism, a frictionally driven winding shaft, a gear secured to said winding shaft, a tributary shaft driven by said gear, a pair of revolving elements carried by said tributary shaft, and a stop member controlled by predetermined conditions of a tape to be coiled by 65 said winding mechanism comprising a member presented into or withdrawn from the path of said revolving elements for thereby arresting said winding shaft and preventing its response to its frictional driving medium.

5. In a power driven coil winding mechanism, a main operating shaft, a winding spool carried by said shaft, a tributary operating shaft driven by said main operating shaft, means for controlling said main operating shaft through said 75

- tributary shaft, and pawl and ratchet mechanism for permitting the free movement of said main operating shaft in one direction independently of said tributary shaft.
5. 6. In a tape winding mechanism, a frictionally driven winding shaft, a gear carried by said winding shaft, a tributary shaft driven by said gear, revolving elements carried by said tributary shaft, single directional driving engagement between said winding shaft and said tributary shaft, and a stop member controlled by a condition of the tape coil on said winding shaft including a member presented into or withdrawn from the path of said revolving elements for arresting said winding shaft.
7. In a tape winding mechanism, a winding shaft, a motor for rotating said shaft, a frictional driving element between said motor and said shaft, a plurality of vanes driven by said shaft, 20 a guide member rotatable into and out of operative position for aligning tape wound on said shaft, and a tape sensing arm comprising an element responsive to a taut condition of said tape or to the rotation of said guide member out of 25 operative position for blocking the revolution of said vanes and for thereby preventing the rotation of said shaft.
8. In a tape winding mechanism, a horizontal winding shaft, a motor for rotating said shaft, a 30 resilient driving element between said motor and said shaft yieldable to predetermined resistance to rotation by said shaft, a guide member rotatable into operative position for aligning tape wound on said shaft, a tape sensing arm responsive to the taut condition of said tape or to the 35 rotation of said guide member out of operative position for arresting said motor, and ratchet means associated with said shaft for permitting the unwinding of the tape during the arrested 40 condition of said shaft and motor.

9. In a tape winding mechanism, a frictionally driven winding shaft, a gear loosely carried by said shaft, pawl and ratchet engagement between said shaft and said gear for permitting the independent rotation of said gear in one direction, 5 and a stop member for arresting said shaft operable through the intermediate agency of said gear.

10. In a tape winding mechanism, a horizontally disposed winding shaft having a reel carried 10 thereby to wind coils of flat stock material, a motor for driving said shaft, frictional driving means between said motor and said shaft, a stop element for arresting the response of said shaft to said motor, and means to permit the free rotation of said shaft in a direction opposite to its winding rotation comprising a gear carried by 15 said shaft constituting the intermediary between said shaft and said stop means, and pawl and ratchet connection between said gear and said 20 shaft.

11. A winding apparatus comprising an arbor shaft, an arbor control shaft, and gear means connecting said arbor shaft and said control shaft including binding means operative to secure 25 said gear means to one of said shafts in the winding direction only, and to permit slip connection in the opposite direction.

12. A tape winder comprising a reel, an electric 30 motor, frictional driving connection between said electric motor and said reel, a circuit connecting said motor with a source of current supply, brake means for arresting the rotation of said reel, and means under the control of a pivoted guide arm 35 for initiating said brake into operation and for concurrently breaking said circuit connection.
